(57) **CLAIM**

The ornamental design for a bottle, as shown and described.

DESCRIPTION

FIG. 1 is a front, right side perspective view of a bottle, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line showing in the figures is for the purpose of illustrating portions of the bottle that form no part of the claimed design; and the dash-dot-dash line defines a boundary of the claimed design and forms no part thereof.
